Primary Examiner — Robert M Spear*Assistant Examiner* — Darcey E Heflin(74) *Attorney, Agent, or Firm* — Sterne, Kessler, Goldstein & Fox PLLC.(57) **CLAIM**

The ornamental design for a tire, as shown and described.

DESCRIPTION

FIG. 1 is a perspective view of a tire showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged view taken along lines 8-8 and 8'-8' in FIG. 2; and,

FIG. 9 is an enlarged cross-sectional view taken along line 9-9 in FIG. 8.

In the drawings, the broken lines showing portions of the tire tread, sidewall and inner bead depict portions of the tire that form no part of the claimed design. In FIGS. 1, 2 and 8, the outermost broken line of the sidewall forms the boundary of the claim.
